UNITED STATES PATENT OFFICE.

VIRGIL G. BANKS, OF MOUNT KISCO, NEW YORK.

TIE-PLATE AND RAIL-BRACE.

970,414.

Specification of Letters Patent. Patented Sept. 13, 1910.

Application filed May 6, 1910. Serial No. 559,696.

To all whom it may concern:

Be it known that I, VIRGIL G. BANKS, a citizen of the United States, residing at Mount Kisco, in the county of Westchester 5 and State of New York, have invented certain new and useful Improvements in Tie-Plates and Rail-Braces, of which the following is a specification.

This invention relates to improvements in 10 rail fastenings, and has for one of its objects to provide a plate disposed between the base of the rail and the tie, and provided with means to prevent the lateral displacement of the rail.

15 Another object is to provide a device of this class having means integral therewith, for engaging one edge of the base of the rail, at the outer side of the track, together with means for engaging in the surface of 20 the tie.

A still further object is to provide a plate disposed between the rail and the tie, having means for engaging the base of the rail on its outer side and means for engaging in the 25 be more fully hereinafter described and means for engaging the tie at the other side of the rail.

With these and other objects in view, the invention consists in the construction, combination and arrangement of parts, as will be more fully hereinafter described and pointed out in the claims, but it will be understood that changes in the specific structure may be made within the scope of 35 the claims, without departing from the spirit of the invention.

In the drawings, Figure 1, is a vertical cross-section through a rail and tie showing my device applied, Fig. 2, is a side elevation 40 of a rail, showing the device applied, Fig. 3, is a top plan view, Fig. 4, is a top plan view of one form of tie plates, Fig. 5, is a section on the line 5—5 of Fig. 4, Fig. 6, is a top plan view of a modification of the 45 plate, and, Fig. 7, is a view of a blank, showing the method of cutting the plates therefrom, to best economize material. Fig. 8, is a longitudinal section through the plate before the tongues have been bent therefrom, Fig. 9, is a cross-section of a rail and fish plates, showing the use of the device therewith.

50 Referring to the drawings, 10 represents a tie of any suitable form or material, and 11 a rail having a base 12. The base 12 is adapted to rest on a plate 13, as seen in Fig.

4, which plate has the parallel ends 13' and 14, the end 14 of which is somewhat shorter than the other end, and connected by the converging sides 15. Formed in the smaller 60 end of the plate is an opening 16 for the spikes, and at the larger end and adjacent the corners thereof, are also spike holes 16'. The plate 13 is so placed on the tie, that the larger end 13' is disposed on the outside of 65 the rail, and spikes driven through the holes 16', while the other end accommodates only one spike. The object of using two spikes on the outside of the rail, is to form a secure brace, to prevent the rail spreading. Spreading rails are not generally due to loosening of the inner spike, but to the shearing off 70 of the head or complete displacement of the outer spike. For this reason, I have seen fit to use two spikes at the outer side of 75 the rail.

At the larger end of the plate 13, it is cut on the parallel lines 17, and transversely cut at 18 to form the two angular tongues 19 and 19', the outer one 19, being bent up on 80 the line 20 and having its free end engage with the outer edge 12' of the base of the rail, and the other one, bent downwardly and forced into the surface of the tie, thus the face 21 of the tongue 19' will abut against 85 the cut formed thereby and prevent lateral movement of the plate. As best seen in the sectional view of Fig. 8, the plate is cut on an angular line 18' so that when the tongues 19 and 19' are respectively bent up and 90 down, the faces 21 of the tongues, will be vertical, and provide the sharpened edge 22 of the lower tongue, to better insure forcing said tongue into the tie. As above described the tongue 19 engages the base of the rail, 95 but as shown in Fig. 9, said tongue will bear against the edge of the fish plate 23.

The smaller end 14' of the plate is formed with a depending transverse biting lip 24, adapted to be driven into the surface of the 100 tie, and forms a secondary gripping member. In the form shown in Fig. 1, the opening 16 is made use of and the spike comes between the lip 24 and the inner edge of the base of the rail. In the form shown in Fig. 9, the 105 biting lip 24' has the flattened face 25, and the adjacent biting edges 26, which lip is driven into the tie as in the other form, but has the advantage that the sharpened edges would bite into the face of the tie, should the plate 13 become loosened and tend to slide along the tie. Also the biting edge 22

of the tongue 19' would bite into the tie and prevent any lateral movement, thus insuring a double grip to the surface of the tie. The opening 16 cannot be used in this form, as 5 the fish-plate would extend beyond the base of the rail, and the fish-plate on the outer side of the rail, engaging the lip 19 makes it necessary to move the plate 13 outwardly to accommodate the portion 23' of said fish-plate, and thus bring the opening 16 under 10 the inner edge of the base of the rail. The spikes on the outer side of the rail would be used as in the other form, but the spikes at the inner side of the rail would be driven 15 beyond the inner end of the plate 13.

In Fig. 6, I have shown a slight modification in the construction of the plate 13, wherein only one spike hole is provided at the larger end of the plate, and on either 20 side of said hole is formed a pair of tongues 19 and 19', the auxiliary tongues, or the added tongues taking the place of the second spike, in the first form.

Fig. 7, illustrates the method of cutting 25 these plates from a blank, with the minimum amount of waste material, a blank from which, four of these plates are cut, leaving only the small right triangular end pieces 27. The outer end of the plate being larger, 30 provides a greater surface in which to form the spike openings and tongues.

From the foregoing, it will readily be seen, that I have provided a simple, and inexpensive rail fastening, and one which will 35 effectively prevent the spreading of the rails, and which is adapted to be made of a single piece.

What is claimed is:

1. A rail fastening comprising a plate

adapted to be interposed between a rail and 40 a tie, said plate being of approximately trapezoidal form, the smaller end of said plate being formed with a cutting lip for engagement with the tie, said cutting lip being provided with parallel rectangular cutting 45 edges, and the larger end of said plate being cut therethrough, said cuts being in the form of an H, and providing an upwardly bent tongue to engage the edge of the rail, and a downwardly bent tongue provided with a 50 cutting edge adapted to bite into the upper face of the tie.

2. A rail fastening comprising a plate adapted to be interposed between a rail and tie, said plate being of approximately trapezoidal form, the smaller end of said plate being formed with a cutting lip for engagement with the tie, said cutting lip being provided with parallel rectangular cutting edges, and the larger end of said plate being 60 cut therethrough, said cuts being in the form of an H, and providing an upwardly bent tongue to engage the edge of the rail, and a downwardly bent tongue provided with a cutting edge adapted to bite into the face of 65 the tie, the cross line of cut of the H being made through the plate obliquely to the plane of the plate, so that when one of said tongues is bent upwardly and the other bent downwardly, the faces of their free ends 70 will lie in the same vertical plane.

In testimony whereof I affix my signature, in the presence of two witnesses.

VIRGIL G. BANKS.
